RECEPTACLE

Louis Vincent Aronson, Newark, N. J., assignor to
Art Metal Works, Inc., Newark, N. J., a cor-
poration of New Jersey

Application March 7, 1934, Serial No. 714,511

11 Claims. (Cl. 220—38)

The invention relates to receptacles and has as an object the provision of a receptacle for personal use, such for instance as a pocket case for cigarettes.

5 It is an object of the invention to provide a receptacle of this character that can be opened for convenient access to the contents with one hand of the user.

It is a further object of the invention to provide 10 a receptacle that will open at both a side and an end by one movement.

It is a further object of the invention to provide 15 a receptacle provided with a sliding closure that may be conveniently opened, as by one thumb, which in its opening will open both at a side and an end and which when closing will automatically close both side and end.

Further objects of the invention will appear 20 from the following description when read in connection with the accompanying drawing showing an illustrative embodiment of the invention, and wherein:—

Fig. 1 is a plan view;

Fig. 2 is an end view;

25 Fig. 3 is a transverse section on line 3—3 of Fig. 1;

Fig. 4 is a vertical section on line 4—4 of Fig.

1; and

30 Fig. 5 is a side elevation of the receptacle with the cover slid to open position.

As shown the device comprises a body formed of a bottom 10, an end wall 11, and side walls 12 and 13. To close an open side of the receptacle, there is shown a sliding closure comprising 35 a plate 14 having flanges 15 and 16 overlapping the sides 12 and 13 respectively, and desirably, though not necessarily, having a flange 17 overlapping the end 11 of the body member.

To slidably connect the flanges 15, 16 with the 40 sides 12, 13, the said sides are formed with longitudinal grooves 18, 19 and the flanges 15, 16 are shown as inturned at their free edges as at 20, 21, the inturned edges engaging in the grooves 18, 19.

45 It will be seen that the closure may be slid freely off from the end of the body member and replaced thereon by an opposite movement.

The end flange 17 has the function of limiting the closing movement of the slidable closure.

50 To close the open end of the body, there is shown an end closure 22 hinged to an end of the side closure as by means of a hinge 23, preferably of piano type. To urge the closure 22 to closed position, there is shown a spring acting in torsion coiled about the pintle of the hinge and having

one end 24 anchored against the side closure and the remaining end anchored and pressing against the end closure 22.

With the construction shown, the receptacle 5 may be held in the palm of the hand and the thumb may be pressed against the sliding closure and thereby move it conveniently to open or closed position. When the sliding closure is moved to open the receptacle, the end closure 22 will by contact with the corners of the open side 10 be forced open and will slide in contact with the edges of the sides 12, 13, in the manner indicated in Fig. 5. When the sliding closure is moved to its closed position, the end closure 22 will be automatically also moved to closed position by 15 action of the spring. The end closure being pressed against the end of the receptacle by the spring will prevent accidental sliding movement of the side closure and thereby keep the receptacle closed except when intentionally opened. 20

For convenience in manipulation, the sliding closure may be provided with a boss 26 which may be of any desired ornamental character.

Minor changes may be made in the physical 25 embodiment of the invention within the scope of the appended claims without departing from the spirit thereof.

I claim:

1. A receptacle comprising, in combination: a 30 member having a side opening and an end opening; closure means slidably associated with one of said openings; means carried by said closure to automatically open and close the remaining opening when said closure is moved to open and closed positions respectively; and spring means 35 reacting between the respective closure means to urge one of them toward closed position.

2. In a device of the class described: a receptacle having a side opening and an end opening; closure means for one of said openings slidably 40 associated with said receptacle; closure means for the remaining opening pivotally mounted on said first named means; and spring means reacting between the respective closure means to urge one of them toward closed position.

3. In a device of the class described: a receptacle having a side opening and an end opening; closure means for one of said openings slidably 45 associated with said receptacle; closure means for the remaining opening pivotally mounted on said first named means; and spring means whereby the second named means is moved to closed position when the first named means is moved to closed position.

4. In a device of the class described: a recep- 55

- tacle open at a side and an end; a closure for said open side slidably associated with said receptacle; means carried by said closure to close said open end; and spring means to urge the last 5 named means toward closing position.
5. In a device of the class described: a receptacle open at a side and an end; a closure for said side slidably mounted on said receptacle; a closure for said end pivotally mounted on said slid- 10 able closure; and spring means to urge said second named closure to closing position.
6. In a device of the class described: a receptacle open at a side and an end comprising a bottom, side walls and an end wall; said side 15 walls formed with longitudinal grooves; a slid- able closure for said open side; means carried by said closure to enter and slide in said grooves; and a closure for said open end pivotally mounted on said sliding closure.
- 20 7. In a device of the class described: a receptacle open at a side and an end comprising a bottom, side walls and an end wall; said side walls formed with longitudinal grooves; a slid- able closure for said open side; means carried by said closure to enter and slide in said grooves; a closure for said open end pivotally mounted on said sliding closure; and spring means reacting be- 25 tween said closures to urge said end closure toward closed position.
- 25 8. In a device of the class described: a receptacle having an open side and end comprising a bottom wall, side walls and an end wall; said side walls formed with exterior longitudinal grooves; a slid- able closure for said open side 30 formed with marginal flanges overlapping said side walls; means carried by said flanges entering and sliding in said grooves; a closure for said open end pivoted upon said slidable closure; and
- spring means reacting between said closures to urge the end closure to closed position.
9. In a device of the class described: a receptacle having an open side and end comprising a bottom wall, side walls and an end wall; said 5 side walls formed with exterior longitudinal grooves; a slidable closure for said open side formed with marginal flanges overlapping said side walls and end wall; the edges of said side wall lapping flanges inturned and entering said 10 grooves; a closure for said open end hinged upon an edge of said slidable closure; a spring carried by the pintle of said hinge, the ends of said spring reacting respectively on said slidable and end closures to urge said end closure to closing posi- 15 tion.
10. A receptacle comprising, in combination: a box having an open side and end; a closure for said open side slidable upon said box between open and closed positions; a closure for said open 20 end pivotally carried by said first named closure; and means to prevent accidental sliding move- ment of said first named closure from closed position.
11. A receptacle comprising, in combination: a body member formed with an open side and end; 25 a closure for said open side, slidably associated with said body member; a closure for said open end pivotally mounted on said first named closure and overlying the edges of the side walls of the body member when in open position; spring 30 means reacting between said closure members to urge said end closure to closing position; whereby impingement of said end closure upon the corners of said side walls overcomes said spring action 35 when said side closure is moved to open position.

LOUIS VINCENT ARONSON.
